UNITED STATES PATENT OFFICE.

GEORGE M. RICHARDS, OF PHILADELPHIA, PENNSYLVANIA.

MULTISTAGE UNLOADER.

1,422,376.

Specification of Letters Patent. Patented July 11, 1922.

Application filed July 3, 1918. Serial No. 243,140.

To all whom it may concern:

Be it known that I, GEORGE M. RICHARDS, a citizen of the United States, residing at 7813 Norwood St., Chestnut Hill, Philadelphia, in the county of Philadelphia and State of Pennsylvania, have invented a certain new and useful Multistage Unloader, of which the following is a specification.

The purpose of my invention is to provide for unloading an air compressor system with a minimum of loss of energy and without freeing air which has been compressed.

A further purpose is to avoid waste of air used to operate the unloader.

15 A further purpose is to form the proper time relation, unloading the low pressure compressor cylinder, emptying the intercooler and unloading the high pressure cylinder in proper sequence.

20 A further purpose is to provide a new type of trigger valve for a pressure unloader.

Further purposes will appear in the specification and in the claims.

25 I have preferred to illustrate my invention by but two forms, showing combinations which are practical, efficient and thoroughly reliable and which at the same time well illustrate the principles of my invention.

30 Figures 1 and 2 are end elevations of portions of multi-stage air compression systems showing two similar forms, identical in so far as relates to my invention.

35 Figure 3 is a vertical central section through a trigger valve embodying my invention.

In the drawings similar numerals indicate like parts.

40 Efficient unloading of a multi-stage air compression system requires that the low pressure cylinder be unloaded first, the intercooler emptied next and the high pressure cylinder unloaded last and with a minimum waste of air and energy. My invention supplies a valve device for operation upon a pressure unloader between the high pressure cylinder and the receiver which is actuated when the intercooler pressure becomes

45 sufficiently low, and is therefore dependent upon the prior actuation of either a suction unloader or a pressure unloader connected with the low pressure cylinder. Because of the fact that this valve device "sets off" the 50 unloading operation, determining the time

and performing the unloading function, it has come to be a trigger in the language of the trade and will be referred to herein as a trigger valve.

The compressors with which my invention 60 is intended to be used are motor driven, and it is quite desirable to relieve the motor automatically until a predetermined speed has been reached; also to cut out the load or put it in again at predetermined pressures. 65

In Figure 1 I have shown low pressure cylinder 5, high pressure cylinder 6, intercooler 7, connecting pipes 8 and 9 and an intake 10 for the low pressure cylinder. In this intake I show a suction unloader 11, of 70 which a number of forms are well known in the art, in connection with a trigger valve 12 controlled by the pressure from the air receiver (not shown) through a pipe 13. The valve 14 permits hand control of the 75 flow through this pipe.

The form of trigger valve 12 illustrated for the suction unloader is a form invented by me and now upon the market but is so well known to the trade as to require no further explanation than that which has been given and the fact that this is distributed by Yarnall-Waring Company of Philadelphia, in connection with suction unloaders to which it is suited. Its specific character 80 forms no part of my present invention, to which any form of suction unloader and trigger valve therefor are suited. The construction of this trigger valve 12 will be clear by reference to my Patent No. 1,286,781, 85 issued December 3, 1918, entitled Fluid-actuated controlling device.

Between the high pressure cylinder 6 and the discharge pipe 15 therefrom to the receiver, I place a pressure unloader 16 which 95 discharges through pipe 16'. There are various recognized forms on the market, manufactured by Yarnall-Waring Company among others, all of which require a trigger valve to operate them. Any of these 100 will answer, as the present invention does not involve the detailed character of the pressure unloader.

A trigger valve suitable for operation of the pressure unloader at this point for carrying out my invention is shown at 17 and is connected with the air receiver by a pipe 18 and with the intercooler by a pipe 19 controlled by hand valve 20. For convenience the pipe 18 is shown as connected with the 110

same pipe line from the receiver as that which supplies pipe 13.

The same connections and trigger valve are shown in Figure 2 as in Figure 1, except that the low pressure cylinder is unloaded by a pressure unloader 11' on the discharge side of the cylinder instead of by a suction unloader, on the inlet side thereof. Where the suction unloader is used the partial 10 vacuum caused in the low pressure cylinder results in a loss of energy there as compared with a system such as is shown in Figure 2.

In either event the same character of pressure unloader is used for the high pressure cylinder with the trigger valve connected in the same way, as the character of low pressure unloading used does not affect the present invention.

In the form of trigger valve shown at 17 20 the body 21 is provided with a seat 22 for a diaphragm 23. It is clamped upon the seat by a cap 24 and bolts 25. The upper surface of the diaphragm (in the position shown) is open to the atmosphere through aperture 26. The diaphragm can be moved by hand in a downward direction by lifting the outer end of a lever 27 which surrounds it at the inner end and is cushioned from the diaphragm by a washer 28. The lever fulcrums 30 against the lower edge 29 of the cap opening through which it extends.

Upon one side of the diaphragm (the upper as shown) lies a skeleton pin 30 which carries oppositely facing valves 31 and 32. 35 These cooperate with valve seats 33 and 34 about openings 35 and 36. With the diaphragm in the position shown, the valve 31 closes against the seat 33 while with movement of the diaphragm in a downward direction, this valve is opened and the valve 32 closes against seat 34.

In order to provide for manufacture and assembly of the parts the upper part of the cap, carrying seat 33 and passage 34 is made 45 separate from the lower part and is threaded into it. This upper part contains a wool yarn filter 37.

The preferably convex head 38 of a bolt 39 is pressed against the under side of the diaphragm by a helical spring 40 which at one end surrounds the stem of the pin and at the other surrounds the stem of a terminal 41. Adjustment of the spring is effected by means of a screw 42 whose end rests in a 55 recess within the terminal. The screw passes through a plug 43, by which the lower end of the trigger valve body is closed, and is locked in adjusted position by nuts 44, 45.

The space 46 between the valve seats 32 60 and 33 is connected with the pressure unloader 16 by a pipe 47 and the space 48 below the diaphragm is connected with the pipe 19 as at 49.

The compression of spring 40 is intended 65 to be very light so that it will not do much

more than support the parts and so that any desired extent of overbalance of atmospheric pressure above the diaphragm as compared with a partial vacuum in the intercooler will cause the diaphragm to depress.

The screw 41 provides quite a delicate adjustment of the parts so as to operate the diaphragm under any degree of vacuum which may be desired. This is set initially or may be changed during operation to suit 75 the needs of different service conditions or the purpose or whim of the user.

In the initial condition of the trigger valve shown in Figure 3 the spring more than counterbalances the weight of the parts, 80 closing the valve 31 against its seat 33 and opening the pressure unloader 16 to atmospheric pressure through valve 32.

When the system shown in Figure 1 is started there is no pressure in any part of it. 85 There being no pressure on the trigger valve of the suction unloader the pipe 10 is fully open to the atmosphere and the low pressure cylinder immediately begins to accumulate pressure in the intercooler from which the 90 high pressure cylinder draws to fill the receiver. This condition obtains and no change takes place in the trigger valve of either unloader until the pressure in the receiver reaches its predetermined upper limit, when 95 the pressure upon trigger valve 12 is effective to operate the suction unloader and close the pipe 10. The supply of air for the low pressure cylinder being cut off, it ceases to supply the intercooler. Meantime the 100 high pressure cylinder quickly reduces the pressure in this intercooler until finally a vacuum condition there is attained.

When the intercooler reaches the predetermined degree of vacuum, the air pressure 105 upon the upper face of the diaphragm, added to the weight of the parts, overcomes the support of the spring 38 and the valve 31 opens at the same time that valve 32 closes. This allows pressure from the receiver to 110 pass through the opening 35 and pipe 47 to the pressure unloader 16 operating it and relieving the high pressure cylinder.

The operation of the system shown in Figure 2 is the same except that the discharge 115 from the low pressure cylinder is released instead of throttling its intake.

It will be noted that the low pressure cylinder, intercooler and high pressure cylinder are lowered in pressure in turn, with a time 120 element between their several operations; and this time element may be made practically whatever may be desired. It will be evident also that extremely little of the receiver air is discharged as the amount required for operation is merely sufficient to operate the two unloaders, saving the waste inherent in previous attempts to attain similar functions.

It will be noted that the connections from 130

the receiver to the two unloaders are entirely independent, functionally, and can be used by wholly distinct and separate pipes, as in Figure 2, the use of the section of pipe 5 in common in Figure 1 being a mere convenience. The two connections with the receiver are thus in parallel or multiple, as distinguished from a series connection of one through the other.

10 The diaphragm is considered herein broadly as a pressure-operated member.

I prefer to operate the trigger valve at intercooler pressures close to the atmospheric pressure and which may range advantageously from a slight pressure above the atmosphere to any desired pressure below.

15 As I can get the range desired by placing the spring below the pressure-operated member and would not require downward pressure by the spring upon the member unless I

20 desired to operate the trigger valve at intercooler pressures higher above the atmosphere than I consider desirable for the most economical operation of the system, I have

25 not deemed it necessary to illustrate any other position of the spring than the upwardly pressing position shown though I have worded my claims so as to protect against unauthorized use with the spring in

30 either position.

Having thus described my invention, what I claim as new and desire to secure by Letters Patent, is:

1. In a multi-stage unloader system, high 35 and low pressure cylinders and an intercooler between them, in combination with a separate unloader and associated trigger valve for each cylinder, one unloader being a pressure unloader in the discharge pipe 40 and which is initially unloaded, and common pressure supply for each trigger valve.

2. In a multi-stage unloader system, high 45 and low pressure cylinders, and an intercooler between them, in combination with an unloader for each cylinder, a trigger 50 valve for each unloader, a receiver fed by the high pressure cylinder, a connection from the receiver to each trigger valve and a connection from the intercooler to the trigger for the high pressure cylinder unloader.

3. In a multi-stage unloader system, high 55 and low pressure cylinders, and an intercooler between them, in combination with an initially unloaded unloader for the discharge pipe of the high pressure cylinder, a trigger valve for the unloader, a receiver fed by the high pressure cylinder and connections from the receiver and intercooler 60 to the trigger valve.

4. In a multi-stage unloader system, high 65 and low pressure cylinders, an intercooler between them and a receiver fed by the high pressure cylinder, in combination with unloaders for the high and low pressure cyl-

inder, and a trigger valve for the high pressure cylinder unloader, operative by reason of reduction of pressure in the intercooler.

5. In a multi-stage unloader system, high 70 and low pressure cylinders, an intercooler between them and a receiver fed by the high pressure cylinder, in combination with an unloader for the high pressure cylinder and a trigger valve for the unloader connected with the intercooler 75 containing a pressure member open to the atmosphere on one side and to the intercooler pressure on the other side and adapted to operate when the intercooler pressure falls to a predetermined point.

6. In a multi-stage unloader system, high 80 and low pressure cylinders, an intercooler between them and a receiver fed by the high pressure cylinder, in combination with an unloader for each cylinder, the high pressure unloader discharging to the atmosphere, a trigger valve for the low pressure unloader, connected with the receiver to operate by reason of excessive receiver pressure, a trigger valve for the high pressure cylinder, connections between the high pressure unloader, trigger valve and the intercooler to operate with decreasing intercooler pressure at a predetermined point and connections between the trigger valve and the receiver to utilize the receiver pressure for operation of the high pressure unloader when the trigger valve has operated.

7. In a multi-stage system unloader, high 85 and low pressure cylinders and an intercooler between them, in combination with an unloader and trigger valve for the low pressure cylinder, an unloader for the high pressure cylinder, a receiver connected with the high pressure cylinder, a trigger valve 90 for the high pressure cylinder unloader, connections from the receiver to the trigger valve to operate the unloader with operation of the trigger valve, a diaphragm in the trigger valve, a valve controlled by the diaphragm to close discharge from the unloader and admit receiver pressure therein when the diaphragm moves, the one surface of the diaphragm being open to atmospheric pressure, a spring pressing against the diaphragm and fluid connections between the diaphragm and the intercooler to cause the atmospheric pressure to move the diaphragm when the intercooler falls to a predetermined point.

8. A pressure unloader in combination 100 with a trigger valve therefor having fluid connection for receiver pressure, a valve normally closing said connection and opening the unloader to the atmosphere, a diaphragm 105 normally maintaining the valve in said position and open on one side to atmospheric pressure and fluid connection from the opposite side of the diaphragm adapted to press against the diaphragm and to be 110 115 120 125 130

overcome by the atmospheric pressure when the pressure on this opposite side of the diaphragm is reduced.

9. In an unloader trigger valve, a trigger valve body having openings for connection with the receiver pressure, with the unloader, with the atmosphere and with a source of variant pressure adapted to approach or fall below atmospheric pressure, valves on opposite sides of the unloader connection adapted normally to close the pressure connection and open the unloader connection to the atmosphere and in unloading position to open the pressure to the unloader and close the atmospheric connection to the unloader and a pressure member controlling the operation of said valve, open to the atmosphere on one side and to the variant pressure connection on the opposite side thereof.

10. In an unloader trigger valve, a trigger valve body having openings for connection with the receiver pressure, with the unloader, with the atmosphere and with a source of variant pressure adapted to approach or fall below atmospheric pressure, valves on opposite sides of the unloader connection, adapted normally to close the pressure connection and open the unloader connection to the atmosphere and in unloading position to connect the pressure with the unloader and close the atmospheric pressure connection, a pressure-operated member controlling the operation of said valves open to the atmosphere on one side of the member and to the variant pressure connection on the opposite side thereof and spring support for the member to maintain the parts in normal position until the variant pressure reaches a predetermined value.

11. In an unloader trigger valve, a trigger valve body having openings for connection with the receiver pressure, with the unloader, with the atmosphere and with a source of variant pressure, adapted to approach or fall below atmospheric pressure, valves on opposite sides of the unloader connection, adapted normally to close the pressure connection and open the unloader connection to the atmosphere and in unloading position to connect the pressure with the unloader and close the atmospheric pressure connection, a pressure-operated member controlling the operation of said valves open to the atmosphere on one side of the member and to the variant pressure connection on the opposite side thereof and spring support for the member to maintain the parts in normal position and balance part of the atmospheric pressure.

12. In an unloader trigger valve, a trigger valve body having openings for connection with the receiver pressure, with the unloader, with the atmosphere and with a source of variant pressure adapted to approach or fall below atmospheric pressure,

valves on opposite sides of the unloader connection, adapted normally to close the pressure connection and open the unloader connection to the atmosphere and in unloading position to connect the pressure with the unloader and close the atmospheric pressure connection, a pressure-operated member controlling the operation of said valves open to the atmosphere on one side of the member and to the variant pressure connection on the opposite side thereof, spring support for the member to maintain the parts in normal position and means for adjusting the spring.

13. In an unloader trigger valve, a trigger valve body having openings for connection with the receiver pressure, with the unloader, with the atmosphere and with a source of variant pressure adapted to approach atmospheric pressure, valves on opposite sides of the unloader connection adapted normally to close the pressure connection and open the unloader connection to the atmosphere and in unloading position to connect the pressure with the unloader and close the atmospheric pressure connection therewith, a pressure-operated member controlling the operation of said valve, open to the atmosphere on one side of the member and to the variant pressure connection on the opposite side thereof and a spring pressing against one side of the member and determining the pressure in the variant pressure connection at which the member shall operate.

14. A trigger valve for an unloader, comprising a pressure-operated member having free atmospheric pressure on one side thereof, a spring adapted normally to lift said member, oppositely facing valves, one of them closed when the member is lifted and the other when it is lowered, a connection from a point between the valves to the unloader, fluid pressure connection for the first valve and a connection below the pressure-operated member, the atmospheric pressure on one side of the member and the spring and connection on the other side being adapted to maintain the first valve closed in normal position of the parts but to operate the pressure-operated member and close the second valve when the pressure in the connection falls to a predetermined value.

15. In an unloader trigger valve, a trigger valve body having openings for connection with the receiver pressure and with the unloader, a double valve controlling the passage of receiver pressure to the unloader and open to the atmosphere at an intermediate point, a pressure-operated member adapted normally to hold the valve closed and a hand operated device engaging and moving the member.

16. In an unloader trigger valve, a trigger valve body having openings for connection with the receiver pressure, with the unloader,

with the atmosphere and with a source of variant pressure adapted to approach or fall below atmospheric pressure, valves on opposite sides of the unloader connection, 5 adapted normally to close the pressure connection and open the unloader connection to the atmosphere and in unloading position to connect the pressure with the unloader and

close the atmospheric pressure connection, a pressure-operated member controlling the 10 operation of the said valve, open to the atmosphere on one side of the member and to the variant pressure connection on the opposite side thereof and hand operated means for moving the diaphragm.

GEORGE M. RICHARDS.
